Attorney

UNITED STATES PATENT OFFICE.

ELMER ARON TAYLOR, OF LADYSMITH, WISCONSIN.

BELT BUCKLE.

Application filed May 21, 1923. Serial No. 640,602.

To all whom it may concern:

Be it known that I, ELMER ARON TAYLOR, a citizen of the United States of America, residing at Ladysmith, in the county of Rusk and State of Wisconsin, have invented certain new and useful Improvements in Belt Buckles; and I do hereby declare that the following is a full, clear, concise, and exact description of the invention, such as will enable others skilled in the art to which it appertains to make and use the same.

This invention relates to improvements in belt buckles, having for an object to provide a belt buckle employing a novel form of clamping lever whereby the free end portion of a belt equipped with the invention may be readily introduced into and firmly secured by the buckle, a portion of said lever being automatically adjustable with relation thereto in order that its positive engagement with the free portion of the belt will be ensured.

It is likewise an object of the invention to provide the clamping lever of the buckle with means for permanently anchoring one end of the belt thereto and yet, which when desired, may be quickly and readily disengaged therefrom.

Other objects will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the same.

In these drawings:

Figure 1 is a vertical longitudinal section through the improved belt taken on the line 1—1 of Figure 3;

Figure 2 is a similar view taken on the line 2—2 of Figure 3;

Figure 3 is a bottom plan view of the improved belt buckle showing the clamping lever in its closed position;

Figure 4 is a similar view wherein the clamping lever is in its open position thereby showing the arrangement of the engaging tongue; and,

Figure 5 is an enlarged detail in perspective of the novel form of clamping lever employed.

Having more particular reference to the drawings, in connection with which like

characters of reference will designate corresponding parts throughout, the improved buckle may be stated to comprise an arcuate body portion designated in its entirety by the numeral 1, having inwardly disposed flanged opposite side portions 2.

Pivotaly mounted between the flanged sides 2 of the body portion 1 and arranged in proximity to the inner side of the arcuate body portion 1 is a clamping lever which I indicate herein, in its entirety, by the numeral 3, said clamping lever having oppositely disposed pairs of apertured bearing ears 4 and 5 formed upon its opposite sides and arranged at substantially right angles thereto as clearly shown in the Figure 5. The bearing ears 5, as will be noted, are employed to effect the pivotal mounting of the lever 3 between the flanged sides 2 of the belt body portion 1 through the medium of a pin 6 passing therethrough and having its opposite ends anchored in the adjacent portions of said flanged sides, as indicated in the Figure 4.

Slidably mounted upon the inner sides of the clamping lever 6 is an engaging tongue 7 having one end thereof curved inwardly as indicated at 8 and adapted to be engaged with an adjacent portion of a belt to be secured by the buckle; the body portion of said tongue having a longitudinally disposed slot or way 9 formed therein, through which guide pins 10 are passed, such pins being securely or fixedly anchored in adjacent portions of the clamping lever 3, as is clearly indicated in the Figure 2. The inner ends of these pins 10 are upset and in consequence, will serve to prevent lateral displacement of the engaging tongue 7 with relation to the clamping lever, yet, permit of longitudinal sliding adjustment thereof to the limit of the opposite ends of the longitudinally disposed slot 9.

Mounted upon the opposite end and adjacent the other side of the clamping lever 3 is a secondary clamping lever 11 having a series of right angularly disposed teeth 12 formed thereon adjacent its pivotal mounting between the apertured bearing ears 3; such mounting, as will be noted upon reference to the Figure 5, being effected by the passing of a pivot pin 13 into engagement with the opening of said bearing ears 4 and then upsetting or anchoring the opposite ends of the same therein. The pivotal mounting of the secondary clamping lever

11 in the bearing ears 4 is such as to provide a way as between the right angularly disposed teeth 12 thereof and the adjacent side of the clamping lever 3 in order that 5 one portion of a belt may be passed therethrough and then permanently connected to the belt buckle. In order that the clamping lever 11 may be swung or moved to its full clamping position, the inner end thereof is 10 preferably formed with a recessed or notched portion 14, which, as shown in the Figures 3 and 4, permits the same to engage over the adjacent head of the guide pin 10.

15 In using my improved belt buckle, one end of a belt indicated in dotted lines in the Figure 1 is passed into the way between the pivotally mounted end of the secondary clamping lever 11 and the adjacent portion 20 of the belt buckle body 1, whereupon said lever is swung to its closed clamping position, at which time the right angularly disposed series of teeth 12 will have biting engagement with the belt and in consequence, 25 clampingly engage the same and thereby effect a positive connection with the belt buckle body portion. The opposite portion of the belt is passed about the body of a wearer whereupon the free end thereof is passed between the inner side of the belt buckle body portion 1 and the pivoted end of the clamping lever 6, the latter being swung to its open position, which is as indicated in the Figure 4, or is at substantially right angles to said 35 body portion. With the free end of the belt properly engaged, the clamping lever is now swung inwardly whereupon the curved end 8 of the engaging tongue 7 will have clamping engagement with the adjacent portion of the inner side of said free end of the belt and thus, will securely connect the same to the body portion 1. With the imparting of a pull to the free portion of the belt, it will be understood that sliding 40 movement of the engaging tongue 7 in a corresponding direction will be permitted, such as indicated in dotted lines in the Figure 2. However, because of the arcuate formation of the belt buckle body portion 1, such sliding movement of the engaging tongue 7 with its curved end 8 will serve only to effect a more positive connection with the free portion of the belt and in consequence, securely connect the same to the 45 body portion. When it is desired to release the free portion of the belt from the buckle, the clamping lever 3 need only be

50 swung outwardly in the direction indicated by the arrows in the Figures 1 and 2, whereupon the curved end 8 of the engaging tongue 7 will be immediately disengaged from the adjacent portion of the inner side of the belt and the said belt may be then freely removed from its engagement with the body portion 1.

55 Manifestly the construction shown is capable of considerable modification and such modification as is within the scope of my claims, I consider within the spirit of my invention.

70 I claim:

75 1. A belt buckle comprising an arcuate body portion having flanged opposite sides, a clamping lever pivotally mounted between said flanged sides adjacent the inner side of the body portion, an engaging tongue on the outer side of said lever having a longitudinal slot formed in the body portion thereof, stop pins fixedly engaged in the body portion of said clamping lever and slidably engaged in said slot whereby to limit the sliding movement of said engaging tongue with 80 relation to the same, one end of said engaging tongue being curved inwardly for engagement with a free portion of a belt, and releasable attaching means on the inner side of the clamping lever, as and for the purpose set forth.

85 2. A belt buckle comprising an arcuate body portion having flanged opposite sides, 90 a clamping lever pivotally mounted between said flanged sides adjacent the inner side of the body portion and having pairs of oppositely disposed bearing ears formed upon its opposite sides, certain of said bearing ears 95 serving to effect pivotal connection of the lever with said flanged sides, an engaging tongue having one end thereof inwardly curved arranged adjacent the outer side of said clamping lever and formed with a longitudinal slot in its body, stop pins fixedly engaged in the body of said clamping lever and slidably engaged through said slot whereby to limit sliding movement of the 100 engaging tongue with relation to the clamping lever, and a secondary clamping lever pivotally mounted between the remaining pair of apertured bearing ears having right angularly disposed teeth formed upon that end of the same adjacent the pivotal mounting.

105 In witness whereof I have hereunto set my hand.

ELMER ARON TAYLOR.
